UNITED STATES PATENT OFFICE.

JOHN W. BROWN, OF LAKEWOOD, OHIO, ASSIGNOR TO NATIONAL CARBON COMPANY,
A CORPORATION OF NEW JERSEY.

ELECTRIC FURNACE.

987,953.

Specification of Letters Patent. Patented Mar. 28, 1911.

Application filed March 5, 1910. Serial No. 547,406.

To all whom it may concern:

Be it known that I, JOHN W. BROWN, a citizen of the United States, residing at Lakewood, in the county of Cuyahoga and State of Ohio, have invented a certain new and useful Improvement in Electric Furnaces, of which the following is a full, clear, and exact description.

The present invention relates to electric furnaces without regard to the specific means employed for generating the heat from the electric current.

The object of the invention has been to devise an arrangement of sections or series of compartments to produce a ring type of electric furnace with a system of air or gas circulation having advantages in the matters of efficiency and ease and flexibility of operation not hitherto attained.

It has been a further object to devise a furnace of this character in which gaseous fuel can be used in conjunction with the electric heat, with systems of gas or air circulation in cases where it is desirable to secure certain effects.

The above objects and desirable advantages it will be seen are attained by that embodiment of my invention described in the following specification and illustrated in the accompanying drawings, in which—

Figure 1 is a top plan somewhat diagrammatic in character and partly in section following the crooked dotted line 1—1 on Fig. 2 of an electric furnace constructed in accordance with my invention. Fig. 2 is a side elevation of said furnace partly in vertical section following the crooked dotted line marked 2—3—4—5 on Fig. 1. Fig. 3 is an enlarged vertical section through the wall between two adjacent furnace compartments, the section being in the plane indicated by line 2—2 on Fig. 1. Fig. 4 is a similar section in the plane indicated by line 3—3 on Fig. 1. Fig. 5 is a similar section in the plane indicated by line 4—4 on Fig. 1. Fig. 6 is a transverse vertical section in the plane indicated by line 6—6 on Fig. 1.

The furnace as an entirety is comprised of a series of sections L, L', L² etc., arranged to form a ring or endless circuit. Eight of these sections are employed in the particular furnace illustrated in the drawing, arranged so as to form two rows of three in a row, which rows are separated by the longitudi-

dinal wall M, and two end sections. The several sections are additionally separated from each other by vertical transversely extended walls N in which are various flues controlled by valves, by means of which corresponding parts of different sections may be put into communication with each other or with the gas or air supplies.

Each furnace section includes a closed heating chamber A, in which are placed the articles B to be heated, together with suitable resistance material in which said articles are embodied. More or less completely enveloping this heating chamber, in each section, are passageways for gases, such enveloping passageways being so constructed, disposed and controlled as to be capable of utilization for the passage therethrough of gases which shall either be burned therein to produce heat, or, if not burned, to act as heat insulation to prevent or reduce the radiation of heat from the heating chamber walls, or to take up heat from certain sections and transfer and give up this heat to the charge in other sections. In arranging these passageways, I prefer to provide one passageway C, containing checker work c, beneath the heating chamber A, which checker work will permit the passage of the gaseous fluid and will also support the heating chamber and the charge therein. It is also preferred that there should be a conduit C' above the heating chamber in which there should be no checker work, or in which the checker work should be of temporary character and easily removable together with the top of said chamber, so that one can conveniently withdraw the charge through the top of the section after the heating operation has been completed. It further may be desired to have the passageways c² containing checker work at both sides of the chamber A.

Beneath the middle longitudinal wall M of the furnace is a discharge conduit P adapted to be connected with the stack for the escape of the spent gases. Beneath the front and rear longitudinal walls are the mains E, E', for the admission of air; and underneath the transverse separating walls N are branch mains E' connecting the inlet mains E with the discharge main P, there being in these branch mains a valve e² (indicated conventionally in Fig. 1), by which they may be severally placed in communica-

tion either with the inlet mains or the outlet mains as desired. Longitudinally extended gas mains F are also formed in the foundation beneath the furnace adjacent to the air mains, and branches F' thereof likewise extend transversely nearly to the central longitudinal wall M.

In each of the transverse bridge walls N, between two adjacent furnace sections, are 10 various sets of flues which are so arranged and provided with valves that either section on opposite sides of said wall may be placed in communication with the air main or with both the air and gas mains, or both 15 sections and the corresponding parts thereof may be placed in communication with each other.

The vertical flues G, G' in wall N communicate, through horizontal flues g, g', with 20 the heating chambers A in the two adjacent furnace sections. At their lower ends each pair of these flues G, G' converge and are merged together to form a flue G²; and each of these flues G² is connected with an air branch E', there being a valve e to control the flow of gas from said branch to said flue. Each of the flues G² is also connected through a horizontal flue f' with one of the branch gas mains F', there being a valve f 30 in the flue f'. A valve G³ is hung from the lower end of that part of wall N which separates flues G and G', whereby if it hangs vertically the two flues are in communication. If this valve be swung in one direction or the other it will shut off the communication between either flue G, G' and the flue G². In this same bridge wall N and 35 above the flues G, G' are horizontal flues T which establish communication between two adjacent conduits C' C'; and a sliding valve t is provided through which, by the dropping of the valve this communication may be discontinued or by raising it, it may be opened up.

45 In the same bridge wall N are other vertical flues D, D' communicating through flues d, d' with the two passageways C' C' in adjacent sections. At their lower ends these flues D, D' converge and are merged to form 50 the flues D² and these flues communicate with the air branches E', there being valves e to control the flow of air from the branches into the flues D². Horizontal valves f' containing valves f are provided through which 55 gas may flow from the branch gas mains F' into the flues D². A valve D³ is provided in order that the flues D, D' may be placed in communication with each other or either of them placed in communication with the 60 air and gas mains.

In the same bridge wall N are vertical flues H, H' which communicate through a plurality of horizontal flues h, h' with the compartments C², C² containing checker work at the sides of the two adjacent fur-

nace sections. These two flues H, H' converge and are merged together to form the flue H² which communicates with the air branch E' and which contains a valve e. The gas branch F' communicates through a 70 flue f' with the flue H² and contains a valve f for controlling the flow of gas.

There will be formed below the furnace preferably tunnels U into which valve operating means will project so that a workman 75 in these various tunnels can control the position of the valves. There is also around the entire right of furnace sections an inclosed passageway V into which other valve operating means will project. Each furnace 80 section L has an independent cover K removable for charging and uncharging that section.

It is to be understood that this invention, broadly considered, is not restricted to the 85 particular construction and arrangement of flues, mains and valves. Any other arrangement of such parts may be adopted which will permit the admission of gas and air to any section or sections, and from one section and its parts to another section, as required.

In each heating chamber, and at the ends thereof is an electrode S,—which are to be connected with the conductors I, I', according 95 as any heating chamber is to be electrically heated.

In the operation of the furnace I propose heating the several compartments and the charges therein successively, thus advancing 100 the heat treatment through the ring after the general manner of gas fire ring furnaces previously well known. It is my purpose to use the flow of gases from unit to unit in co-operation or in conjunction with the electric heating so as to secure the most desirable 105 effects. Inasmuch as the operation in its broader aspect contemplates the use of a current of air or other non-combustible gas 110 or gases as well as combustible gases, I have used the expression gaseous fluids as referring to all such gases, and I would have the phrase so construed in the specification and claims, except where the phrase is specifically qualified. Owing to the system of 115 conduits and controls which I have arranged, it will be seen that it is possible to use the furnace to advantage with electric current as the sole source of heat, or with the effects of electric heating combined with 120 that of combustion heating.

Contemplating first the use of the furnace with the electric current as the sole source of heat, in which heat insulation and transference is effected by means of currents of 125 air or other gases more or less completely enveloping the charge in each compartment, it may be assumed that the charge in section L has been baked and is sufficiently cool to be removed; that the charge in sections 130

L^1 and L^2 have received their full bake, and are in the process of cooling, and section L^3 is being subjected to the highest heat necessary to effect the desired baking. Under 5 these circumstances air or other non-combustible gas, should any such be obtainable, may be admitted through the vertical flues D, G and H of sections L' so as to flow through the conduits C, C', C² enveloping 10 the heating chamber, and through said heating chamber, and be forced or drawn forward through the ports or passageways described in the conduits C, C', C² of section L², from which they pass through the ports 15 described into corresponding parts of section L³. By this means the previously baked charges in sections or units L' and L² will become more rapidly cooled than would otherwise be the case and the gases passing 20 into the section L³ will have been raised to a very high temperature, so that they serve as an effective insulating medium in passing through the conduits C, C', C² of the unit L³ which is being subjected to the full 25 heat of the electric current. By a similar arrangement of the valves the gases which have passed through the enveloping conduits of the section L² are led through each successive compartment in the entire ring 30 up to the last compartment charged. The gases passing into the furnace of course go in at ordinary temperatures, but in their progress up to the unit subjected to the electric heat they reach a higher temperature in 35 each successive unit at the expense of the heat contents of the walls and charges of the units through which they pass. In passing through the unit under the electric firing, it will be seen that the enveloping gases 40 not only tend to prevent radiation of heat electrically generated in the charge, but they will give up a portion of their heat to the charge, at least in the initial stages of the electric heating, and as they pass from this 45 unit at a very high temperature through the units charged and prepared for baking, they will transfer the heat to the walls of the units and the charges contained therein until the outlet is reached. The effect and 50 advantage of such an operation will be plain. It is to be noted in practical operation that a point will be reached in the electric baking at which the charge will become heated to a temperature higher than 55 that of the enveloping gases, and from this point on to the end of the bake the flow of the enveloping gases should be diminished, maintaining them in a substantially stagnant condition in order to avoid carrying 60 away the heat radiated from the charge, and thus increasing the rate of radiation losses. When the full electric bake has been given and the current transferred to the next succeeding section the flow of air or gases 65 through the furnace may be again instituted

and the process repeated as described. It will be clear, of course, that with such an arrangement there is a wide range of possibility in choosing such gases to pass through the furnace as will produce certain desired 70 chemical or physical effects. In such a case the gases might flow through the heating chambers and the charge itself, as well as through the conduit enveloping the heating chambers.

In the case where the effect of electric heating is combined with that of combustion heating, the general practice will be as that described above. In the case where combustion takes place those units or sections which have been previously subjected to the flue baking heat are in such communication that the incoming gases flow through them cooling off the charge and transferring the heat of the unit under treatment to those 80 units succeeding it. The air or gas, or both, when both are admitted concurrently, are brought in under suitable conditions to prevent combustion until the proper point is reached. Under these conditions the gases 85 act as heat collectors prior to their entrance into section L³, wherein they are burned, and in this section after the internal temperature of the charge exceeds that of the gases the latter act as heat insulators. When the 90 temperature around the charge in section L³ exceeds that around the charge in section L², firing by combustion in section L² may be advantageous in order to prevent heat radiation from section L³ back to L². 100 Likewise it may be desirable to start combustion in section L⁴ as soon as the electric firing is commenced in section L³, also for the purpose of preventing radiation from section L³ during the electric firing period. 105 Of course the furnace is capable of being handled in other manners for securing other effects, but the above clearly illustrates the flexibility of operation of which this furnace is capable, and by which a greater efficiency 110 is obtained than has been possible in any electric furnace heretofore known to me. Owing to the fact that there are many modifications of the described method of operation, I desire that it should be clearly understood that the method described is merely 115 an example illustrative in its character.

As a résumé of the advantages of the furnace I would call attention to the fact that when non-combustible gases are used as described in the first part of the specification, it will be possible to obtain the highest temperatures with great economy owing to the cutting down of radiation losses and to saving of the energy required to heat the walls 120 and the charge up to the point where electric heating becomes efficient. Further it will be quite easy in this operation to recover by-products and to heat the charge in any desired atmosphere, and to maintain the 125 130

charge in the compartment under treatment at a uniform temperature throughout the compartment and to attain the temperature in all of the compartments successively.

5 In the case where combustible gases are used for the purpose of combined combustion heating with electric heating, it will be seen that the highest temperatures may be obtained with maximum efficiency both in 10 respect to fuel and electricity due to the greater temperature obtainable by combustion of gases heated to a high temperature being burned, and to the use of the fuel at a low temperature and the electric heating, 15 together with the fuel at a high temperature, as well as to a maximum decrease in radiation losses of electric heating.

Having described my invention, I claim:

1. An electric furnace of the ring type 20 having a series of sections or units containing independent electric heating means, gaseous fluid conduits being provided in certain of the walls of said sections, the walls between adjacent sections being provided 25 with flues leading to said conduits, a gaseous fluid main with which said flues are connected, and means for regulating the flow of gaseous fluid from the main to the flues.

2. An electric furnace of the ring type 30 having a series of sections or units containing independent electric heating means, gaseous fluid conduits being provided in certain of the walls of said sections, the walls between adjacent sections being provided 35 with two separate sets of flues one set for each section, a gaseous fluid main, means for permitting communication between the said main and either set of flues, or both sets of flues, and means for shutting 40 off the main from the flues.

3. An electric furnace of the ring type

comprising a series of sections or units, each section being provided with a heating chamber at least partially enveloped by conduits for conducting the gaseous fluid, the walls 45 between adjacent sections being provided with flues, certain of said flues connecting with the said conduit, other flues connecting with the heating chamber, a gaseous fluid main connecting with said flues, and valves 50 controlling the connection between the main and the flues.

4. An electric furnace of the ring type having a series of sections or units containing independent electric heating means, 55 gaseous fluid conduits being provided in certain of the walls of said sections, the walls between adjacent sections being provided with separate sets of flues one for each section, said flues merging into a common 60 chamber at one end, a gaseous fluid main connected with said chamber, a valve adapted to separate either of said flues from said chamber, and another valve for shutting off the said main from the chamber.

5. An electric furnace of the ring type having a series of sections or units containing independent electric heating means, gaseous fluid conduits being provided in certain of the walls of said sections, the 70 walls between adjacent sections being provided with separate sets of flues, one for each section, a gas main, an air main connected with the said flues, and means for shutting off the flues from either or both 75 of the said mains.

In testimony whereof, I hereunto affix my signature in the presence of two witnesses.

JOHN W. BROWN.
